CLAIM

The ornamental design for a poultry feed block, as shown and described.

DESCRIPTION

- FIG. 1 is a top, front, right perspective view of a first embodiment of a poultry feed block;
FIG. 2 is a front view thereof, the bottom and back views being identical to FIG. 2;
FIG. 3 is a top view thereof;
FIG. 4 is a right side thereof, the left side view being identical to FIG. 4;
FIG. 5 is a top, front, right perspective view of a second embodiment of a poultry feed block;
FIG. 6 is a front view thereof, the bottom and back views being identical to FIG. 6;
FIG. 7 is a top view thereof;
FIG. 8 is a right side thereof, the left side view being identical to FIG. 8;
FIG. 9 is a top, front, right perspective view of a third embodiment of a poultry feed block;
FIG. 10 is a front view thereof, the bottom and back views being identical to FIG. 10;
FIG. 11 is a top view thereof;
FIG. 12 is a right side thereof, the left side view being identical to FIG. 12;
FIG. 13 is a top, front, right perspective view of a fourth embodiment of a poultry feed block;
FIG. 14 is a front view thereof, the bottom and back views being identical to FIG. 14;
FIG. 15 is a top view thereof;
FIG. 16 is a right side thereof, the left side view being identical to FIG. 16;
FIG. 17 is a top, front, right perspective view of a fifth embodiment of a poultry feed block;
FIG. 18 is a front view thereof, the bottom and back views being identical to FIG. 18;
FIG. 19 is a top view thereof;
FIG. 20 is a right side thereof, the left side view being identical to FIG. 20;
FIG. 21 is a top, front, right perspective view of a sixth embodiment of a poultry feed block;
FIG. 22 is a front view thereof, the bottom and back views being identical to FIG. 2s;
FIG. 23 is a top view thereof;
(Continued)

FIG. 24 is a right side thereof, the left side view being identical to FIG. 24;
 FIG. 25 is a top, from, right perspective view of a seventh embodiment of a poultry feed block;
 FIG. 26 is a front view thereof, the bottom and back views being identical to FIG. 26;
 FIG. 27 is a top view thereof;
 FIG. 28 is a right side thereof, the left side view being identical to FIG. 28;
 FIG. 29 is a top, front, right perspective view of an eighth embodiment of a poultry feed block;
 FIG. 30 is a front view thereof, the bottom and back views being identical to FIG. 30;
 FIG. 31 is a top view thereof;
 FIG. 32 is a right side thereof, the left side view being identical to FIG. 32;
 FIG. 33 is a top, front, right perspective view of a ninth embodiment of a poultry feed block;
 FIG. 34 is a front view thereof, the bottom and back views being identical to FIG. 34;
 FIG. 35 is a top view thereof;
 FIG. 36 is a right side thereof, the left side view being identical to FIG. 36;
 FIG. 37 is a top, front, right perspective view of a tenth embodiment of a poultry feed block;
 FIG. 38 is a front view thereof, the bottom and back views being identical to FIG. 38;
 FIG. 39 is a top view thereof;
 FIG. 40 is a right side thereof, the left side view being identical to FIG. 40;
 FIG. 41 is a top, front, right perspective view of an eleventh embodiment of a poultry feed block;
 FIG. 42 is a front view thereof, the bottom and back views being identical to FIG. 42;
 FIG. 43 is a top view thereof;
 FIG. 44 is a right side thereof, the left side view being identical to FIG. 44;
 FIG. 45 is a top, front, right perspective view of a twelfth embodiment of a poultry feed block;
 FIG. 46 is a front view thereof, the bottom and back views being identical to FIG. 46;
 FIG. 47 is a top view thereof; and,
 FIG. 48 is a right side thereof, the left side view being identical to FIG. 48.
